UNITED STATES PATENT OFFICE.

WILLIAM K. LONG, OF BELLAIRE, OHIO.

DESIGN FOR A LAWN-WEEDER.

SPECIFICATION forming part of Design No. 29,831, dated December 20, 1898.

Application filed November 26, 1898. Serial No. 697,563. Term of patent 14 years.

To all whom it may concern:

Be it known that I, WILLIAM K. LONG, a citizen of the United States, residing at Bellaire, in the county of Belmont and State of Ohio, have invented and produced a new and original Design for Lawn-Weeders, of which the following is a specification, reference being had to the accompanying drawings, forming part thereof.

10 Figure 1 is a perspective elevation of my new design in lawn-weeders, and Fig. 2 is an edge elevation thereof.

As shown in the drawings, the leading or material feature of my design consists of the 15 shape or outline of the blade A, which is distinguished and known by its practically plain flat surfaces a and a' front and rear, its peculiar conformation of lower edge, which is convex at a^2 from side to side, resembling an

arch, and has the appearance of a bevel finish at its rear a^3 from side to side, thus producing the effect upon the eye of a transversely-arched cutting edge on an otherwise plain instrument, whose edges gradually taper toward each other from top to bottom. Above 25 the blade is the socket-shank B, which is relieved just above the upper edge of the blade by a walled oblong opening b , extending through from front to rear.

What I claim is—

30 The design for a lawn-weeder, substantially as herein shown and described.

Witness my hand to the foregoing specification this 19th day of November, 1898.

WILLIAM K. LONG.

Witnesses:

GEO. O. ROBINSON,
S. J. ROCKERSHOUSEN.
